US00D785199S

(12) **United States Design Patent** (10) Patent No.: **US D785,199 S**
(45) Date of Patent: **** Apr. 25, 2017**

(54) **RAIL**

(71) Applicant: **CPG International LLC**, Scranton, PA (US)

(72) Inventors: **Paul M. Bizzarri**, Mason, OH (US); **Chip Herr**, Columbus, OH (US); **John M. Previte**, Dublin, OH (US); **Kevin T. Burt**, Columbus, OH (US); **William G. Taylor**, Columbus, OH (US); **Matthew T. Fenneman**, Gahanna, OH (US); **Jeffrey R. Burr**, Loveland, OH (US); **Timothy C. Rothwell**, Dublin, OH (US)

(73) Assignee: **CPG International LLC**, Scranton, PA (US)

(**) Term: **15 Years**

(21) Appl. No.: **29/561,820**

(22) Filed: **Apr. 20, 2016**

Related U.S. Application Data

(63) Continuation of application No. 13/461,496, filed on May 1, 2012, which is a continuation of application No. 12/831,064, filed on Jul. 6, 2010, now Pat. No. 8,167,275, which is a continuation of application No. 11/292,269, filed on Nov. 30, 2005, now abandoned.

CLAIM

The ornamental design for a rail, as shown and described.

DESCRIPTION

FIG. 1 is a front top perspective view of a rail.

FIG. 2 is a front bottom perspective view of the rail of FIG. 1.

FIG. 3 is a top plan view of the rail of FIG. 1.

FIG. 4 is a right side elevation view of the rail of FIG. 1; and, FIG. 5 is a left side elevation view of the rail of FIG. 1.

The broken lines on the front face and along the length of the rail in FIGS. 1 and 2 indicate portions that are not part of the claimed design. The broken lines on the rear end of the rail in FIGS. 1-5 indicate a break.

1 Claim, 4 Drawing Sheets
